UNITED STATES PATENT OFFICE.

WILLIAM T. CARROLL, OF WORCESTER, ASSIGNOR TO GEORGE DRAPER & SONS, OF HOPEDALE, MASSACHUSETTS.

BAND-TIGHTENER FOR SPINNING-MACHINES.

SPECIFICATION forming part of Letters Patent No. 352,221, dated November 9, 1886.

Application filed May 1, 1886. Serial No. 200,817. (No model.)

To all whom it may concern:

Be it known that I, WILLIAM T. CARROLL, of Worcester, county of Worcester, and State of Massachusetts, have invented an Improvement in Band-Tighteners for Spinning-Machines, of which the following description, in connection with the accompanying drawings, is a specification, like letters on the drawings representing like parts.

10 This invention has for its object to provide a device by which to produce tension upon and take up slack in the spindle-driving band.

Heretofore the driving-band between the drum and spindle-whirl has been acted upon 15 by a sheave mounted upon an axis or stud substantially parallel with relation to the drum, and the pressure of the sheave has been either upon the top or upon the under side of the band, such pressure tending to either

20 depress or lift the band from the center line of the whirl at its deepest point. I have found by experiment that the farther the band is carried about and in contact with the bottom of the groove in the whirl the more positive and accurate the movement of the spindle; and to insure a more extended wrapping 25 of the band about the whirl as the band becomes slack, and also in the normal condition of the band, I have provided a band-controlling or tension device containing a sheave

30 mounted on a substantially vertical stud, so as to place the top side of the said sheave substantially parallel to the top side of the spindle-whirl, the said sheave thus placed acting upon the side of the band and moving it horizontally into the bottom of the groove of the 35 whirl rather than out from the bottom of the said groove, as would be the case if the pressure on the band were vertical.

40 Figure 1 shows a sufficient portion of a spinning-frame with my improvement added to enable my invention to be understood. Fig. 2 is a top or plan view of Fig. 1, the side frame, partially shown in Fig. 1, being omitted; and Fig. 3 is a section of Fig. 2 in the 45 dotted line $\alpha\alpha$, the frame being omitted, the pintle e^2 being shown in elevation.

The end frame, A, spindle-driving drum B, driving-band C, sleeve-whirl spindle D, and bolster-rail a are and may all be of usual construction. At the rear of the bolster-rail, and in line with each spindle, is a stud or pin, p , upon which is mounted a weighted lever or arm, f , the latter having an eccentrically-located hole, 2, to fit the said stud or pin. 50 The lever f has at its lower end a weight, f^2 , and the upper end of the said lever is bored longitudinally to receive the pintle e^2 , to the upper end of which is secured the sheave e^3 , the upper side of the said sheave thus lying 55 substantially parallel with relation to the upper side of the whirl attached to the sleeve of the spindle, the lower side of the sheave turning substantially in the plane of rotation of the center line of the whirl attached to the 60 sleeve of the spindle. The hole 2 is formed in the lever at one side of its center, and the weight f^2 acts normally to keep the sheave e^3 pressed against the side of the band C at its slack side, the pressure of the said sheave 65 against the band being in a direction to not only force the band into the bottom of the groove of the whirl, and thus take up any slack therein, but also to partially bend the band 70 closely about the sleeve-whirl. The lever 75 herein shown normally stands in a nearly upright position.

I claim—

The spindle having a whirl, and the drum to move the spindle-driving band, combined 80 with the lever f , the pintle, and sheave e^3 , the face of which occupying a position in a plane substantially parallel to the face of the whirl on the spindle, the edge of the sheave acting upon the side of the band, forcing it into the 85 bottom of the groove of the whirl and about the said whirl, substantially as described.

In testimony whereof I have signed my name to this specification in the presence of two subscribing witnesses.

WILLIAM T. CARROLL.
